FIG. 3

FIG. 4

FIG. 5

FIG. 1 is a perspective view of a frame for a table or similar article showing my new design;

FIG. 2 is a side elevational view, the side opposite being the same;

FIG. 3 is an elevational view of one of the two identical ends;

FIG. 4 is a top plan view of the invention; and

FIG. 5 is a modified form of the article of FIG. 1 wherein a leg brace or stretcher has been added.

This application is a continuation-in-part of my earlier application Ser. No. D. 11,383, filed Apr. 10, 1968.

I claim:

The ornamental design for a frame for a table or similar article, substantially as shown and described.
